UNITED STATES PATENT OFFICE.

FRED C. CROUSE, OF LOS ANGELES, CALIFORNIA.

SLIDING-DOOR HANGER FOR SECTIONAL BOOKCASES.

1,267,188.

Specification of Letters Patent. Patented May 21, 1918.

Application filed June 26, 1917. Serial No. 177,089.

To all whom it may concern:

Be it known that I, FRED C. CROUSE, a citizen of the United States, residing at Los Angeles, in the county of Los Angeles 5 and State of California, have invented new and useful Improvements in Sliding-Door Hangers for Sectional Bookcases, of which the following is a specification.

This invention comprehends the provision 10 of a sliding door hanger for sectional bookcases, cabinets or the like, and has particular reference to doors which are initially swung from a vertical to a horizontal position, and subsequently slid into the case or 15 cabinet to an opened position.

One of the chief characteristics of the invention resides in the provision of means 20 for guiding and supporting the door upon the partition of the case, thus insuring a perfect action of the door, as the latter is otherwise free from contact with the case, except at two remote points where suitable 25 projections maintain the door spaced from the top of the case, thus protecting the finished surface of the door from injury.

Other objects of the invention will appear as the nature of the same is better understood from the following detail description when read in connection with the accompanying 30 drawing, the invention residing in the construction, combination and arrangement of parts as claimed.

In the drawing forming part of this specification like numerals of reference indicate 35 similar parts in the several views and wherein:—

Figure 1 is a perspective view with the top partly broken away showing the normal position of parts.

Fig. 2 is a view similar to Fig. 1 showing the door in opened position.

Fig. 3 is a vertical sectional view taken on line 3—3 of Fig. 2.

Fig. 4 is a fragmentary detail sectional view showing the manner in which the door 45 is supported for swinging movement.

Referring more particularly to the drawing in detail, the bookcase, cabinet or the like is indicated generally at A and includes a bottom 10, top 11, a rear wall 12 and end walls 13. Secured to the inner surface of each end wall is a vertically disposed cleat 14 which is cut away at its upper end to provide a shoulder 15. Projecting laterally from the opposite ends of the door 16 are pins 17 which normally rest

upon the shoulders 15 for supporting the door for swinging movement. Carried centrally of the door is a vertically disposed channel shaped guide element 18 which when the door is in its closed position embraces the adjacent edge of a vertically disposed partition 19 which divides the case or cabinet into two sections. Projecting from the rear wall 12 is a pair of 60 divergently disposed brace elements 20 which are arranged at the opposite sides of the partition, having their forward corresponding extremities secured to the partition 19 and their opposite ends secured to 70 the rear wall 12.

The guide element 18 is secured to a leaf 21 of a hinge which also includes a leaf 22. The leaf 21 is fixed to the upper portion of the door, while the leaf 22 is associated with 75 the leaf 21 for swinging movement. Carried by the leaf 22 is a channel-shaped guide element 23 which by reason of its association with the movable leaf 22 of the hinge, normally embraces the upper edge of the partition 19 in right angular relation with respect to the guide 18, when the door is closed. The element 23 serves to initially guide the door in its sliding adjustment when the door has been swung from a vertical 80 to a horizontal position, at which time the guide 23 forms a continuation of the guide 18, and when the door has been slid within the casing a short distance the guide 18 embraces the upper edge of the partition 90 19 to assist in guiding the door in its adjustments. With a view of permitting the door to be wholly slid within the case or cabinet, the rear edge of the partition 19 is cut away as at 24 so that when the door 95 has been moved within the casing a predetermined distance the guide element 23 gravitates to assume the position shown in Fig. 3, in which position it does not interfere with the further sliding of the door, 100 and thus permits the same to be wholly moved within the casing to a full opened position.

By reason of this construction, the case or cabinet may be comparatively high with regard to the width of the cabinet, and yet permit the door which is of a height consistent with the height of the cabinet, to be wholly slid within the latter. 105

Again, it will be observed that the entire weight of the door is borne by the 110 partition 19, and that friction is greatly minimized with a view of affording the door

a free action, so that it can be slid into the casing with the least effort and exertion, and also without binding. Projecting from the base of the door adjacent the upper corners thereof, are rounded nail heads or other suitable projections indicated at 11 of which are employed to engage the top 11 of the cabinet when the door is being slid within the latter, thus maintaining the finished 10 surface of the door spaced from the top wall 11 and preventing scratching of the door or otherwise injuring the same. The lower edge of the door may be provided with a finger engaging tab 26 to facilitate moving 15 the door to an opened or closed position, while the door may be fastened in its closed position in any suitable manner.

While it is believed that from the foregoing description the nature and advantages of the invention will be readily apparent, I desire to have it understood that what is herein shown and described is merely illustrative of the preferred embodiment of the invention to which I do not limit myself, and that such changes may be resorted to when desired as fall within the scope of what is claimed.

What is claimed is:—

1. A cabinet including a vertically disposed partition spaced from the top wall of the cabinet, a door mounted for vertical swinging movement and adapted to be slid within the cabinet with the partition constituting a support therefor, and means for guiding the door in its movements across said partition.

2. A cabinet including a vertically disposed partition spaced from the top wall of the cabinet, a pair of divergently disposed brace elements terminally secured to the rear wall of the cabinet and to the opposite sides of the partition, a door mounted for vertical swinging movement and adapted to be slid within the cabinet above the partition, said partition constituting a support for the door, and means for guiding the door in its movements across the partition.

3. A cabinet including a vertically disposed partition spaced from the top wall of the cabinet, a door mounted for vertical swinging movement and adapted to be slid within the cabinet above the partition, said partition constituting a support for the

door, and a channel-shaped element carried 55 by the door and normally embracing the forward edge of the partition, said element embracing the upper edge of the partition when the door is arranged horizontally and serving to guide the latter in its movements 60 across the partition.

4. A cabinet including a bottom, top, rear and end walls, a cleat secured to each end wall and formed to provide a shoulder, a door, pins projecting laterally from the opposite ends of the door and resting upon said shoulders and supporting the door for vertical swinging movement, a vertically disposed partition spaced from the top wall, said door being adapted to be slid within the cabinet 70 above the partition, said partition serving as a support for said door, and means for guiding the door in its movements across the partition.

5. A cabinet including a vertically disposed partition spaced from the top wall of the cabinet, a door mounted for vertical swinging movement and adapted to be secured within the cabinet above said partition, said partition constituting a support for said door, a channel-shaped element embracing the upper edge of said partition and constituting a guide for said door, said partition being cut away at its rear edge, and said element being mounted to gravitate below the upper edge of said partition to an out of the way position to allow the door to be wholly moved within the cabinet.

6. A cabinet including a vertically disposed partition spaced from the top wall 90 of the cabinet, a door mounted for vertical swinging movement and adapted to be slid within the casing above the partition, a channel-shaped element embracing the upper edge of the partition, and constituting a guide for said door, a second channel-shaped element carried by the door and adapted to form a continuation of the first mentioned element when the door is swung to a horizontal position, said partition being 95 cut away at its rear edge, and said first mentioned channel-shaped element being mounted to gravitate over the cut away portion of the partition to an out of the way position to allow the door to be wholly moved 100 within the cabinet.

In testimony whereof I affix my signature.

FRED C. CROUSE.
